UNITED STATES PATENT OFFICE.

WILLIAM R. CRUMP, OF COLLINSVILLE, TEXAS.

WINDOW-SASH.

977,712.

Specification of Letters Patent. Patented Dec. 6, 1910.

Application filed May 31, 1910. Serial No. 564,247.

To all whom it may concern:

Be it known that I, WILLIAM R. CRUMP, a citizen of the United States, residing at Collinsville, in the county of Grayson, State 5 of Texas, have invented certain new and useful Improvements in Window-Sashes; and I do hereby declare the following to be a full, clear, and exact description of the invention, such as will enable others skilled 10 in the art to which it appertains to make and use the same.

This invention relates to improvements in window sashes, more particularly to devices of this character in which the window glass 15 is secured in the sash without the use of putty and similar fastening devices, and has for one of its objects to simplify and improve the construction and increase the efficiency and utility of devices of this character.

Another object of the invention is to provide a device of this character which may be applied without structural changes to sashes of various sizes and to sashes containing 25 any required number of panes of glass.

With these and other objects in view, the invention consists in certain novel features of construction as hereinafter shown and described and then specifically pointed out 30 in the claims; and, in the drawings illustrative of the preferred embodiment of the invention, Figure 1 is a side elevation of the device with the sash constructed in accordance with the improved device, Fig. 2 is 35 a section on the line 2—2 of Fig. 1 with the sash in open position, Fig. 3 is a sectional detail illustrating the arrangement with the sash in open position or arranged to permit the insertion or removal of the panes of 40 glass, and showing the panes of glass partly removed.

The improved device is formed in two sections, preferably divided longitudinally, the sections being represented as a whole 45 respectively at 10—11. Each of the sash sections is formed with outer side members and end members of the usual form and with inner side members represented at 12—13 and united preferably by hinges 14 at one side, and with hooks or other suitable fastening devices 16 at the opposite side. By this arrangement the sash mem-

bers may be maintained in open position, as shown in Fig. 1 and occupy the same relative position as an ordinary sash, and presents the same appearance as an ordinary 55 two-pane sash.

The outer end members of the sash sections 10—11 are provided with glass receiving channels, while the inner members 12—13 are provided with glass receiving slots indicated at 17—18, the slots extending entirely through the members 12—13 so that when the sash sections are arranged in open position as shown in Figs. 1 and 2, the 60 slots 17—18 are continuous, as shown in Fig. 2. By this arrangement it will be obvious that when the sash sections 10—11 are swung upon their hinges 14 into the position indicated in Fig. 3 the slots 17—18 are 65 exposed so that the panes of glass, represented respectively at 19—20, may be inserted into the channels in the slots, and then when the sash sections are arranged in alignment as shown in Figs. 1 and 2, and the 70 hooks 16 connected, the panes of glass will be held in position and prevented from removal, and require no further securing means, care being taken that the panes of 75 glass are so cut that their confronting edges 80 will be located in relatively close engagement, to prevent rattling or looseness.

If preferred the members 12—13 may be formed with a tongue and groove joint represented at 21, to render the joint between 85 the sash sections air-tight, and likewise to increase the strength and relieve the hinges and hooks largely from strain.

What is claimed is:—

1. A window sash formed in two sections 90 having glass receiving channels in their members and arranged edge to edge, the channels of the confronting members of the sash sections being extended entirely through the same to permit the glass to engage edge to edge, hinges uniting the confronting members of the sash sections at 95 one side, and fastening means uniting said confronting members at the opposite sides.

2. A window sash formed in two sections 100 having glass receiving channels in their members and arranged edge to edge, the channels of the confronting members of the sash sections being extended entirely through

the same to permit the glass to engage edge to edge and the adjacent faces of the confronting sash members tongued and grooved longitudinally at one side of the glass receiving channel, hinges uniting the confronting members of the sash sections at one side, and fastening means uniting said confronting members at the opposite side.

In testimony whereof, I affix my signature, in presence of two witnesses.

WILLIAM ^{his} X R. CRUMP.
